US0D1021925S

(12) **United States Design Patent** (10) Patent No.: **US D1,021,925 S**
(45) Date of Patent: ** Apr. 9, 2024

(54) **DISPLAY SCREEN OR PORTION THEREOF WITH GRAPHICAL USER INTERFACE**

(71) Applicant: **Apple Inc.**, Cupertino, CA (US)

(72) Inventors: **Taylor Gerard Carrigan**, San Francisco, CA (US); **Patrick Lee Coffman**, San Francisco, CA (US); **Christopher P. Foss**, San Francisco, CA (US)

(73) Assignee: **Apple Inc.**, Cupertino, CA (US)

(**) Term: **15 Years**

(21) Appl. No.: **29/826,247**

(22) Filed: **Feb. 10, 2022**

Related U.S. Application Data

(63) Continuation of application No. 29/759,444, filed on Nov. 23, 2020, now Pat. No. Des. 945,447, which is a continuation of application No. 29/680,496, filed on Feb. 15, 2019, now Pat. No. Des. 916,867.

CLAIM

The ornamental design for a display screen or portion thereof with graphical user interface, as shown and described.

DESCRIPTION

The sole FIGURE shows a front view of a display screen or portion thereof with graphical user interface showing the claimed design.

The peripheral dashed broken lines depict a display screen or portion thereof, and form no part of the claimed design. The interior broken lines depict portions of the graphical user interface which form no part of the claim design.
